UNITED STATES PATENT OFFICE.

ALBERT C. ASPER, OF BIRD CITY, KANSAS.

WORK HOLDING AND FILING DEVICE.

Application filed August 6, 1925. Serial No. 48,595.

The invention relates to improvements in devices for holding work while accurately filing the same, and has reference primarily to a device of this character which is intended for use in filing main bearing or connecting rod caps, to permit tightening of the bearings.

The principal object of the invention is to provide a device of the character set forth which is simple and inexpensive, may be easily manipulated, will permit any desired quantity of the cap to be filed off, and will insure that the new surface formed by the filing operation, will be in a plane absolutely parallel to the plane previously occupied by the old surface. Thus, a true fitting of the cap against the cooperating part of the bearing is insured.

With the foregoing in view, the invention resides in the novel subject matter hereinafter fully described and claimed, the description being supplemented by the accompanying drawing.

Figure 1 is a side elevation.

Figure 2 is a top plan view partly broken away.

Figure 3 is a vertical sectional view as indicated by line 3—3 of Figure 2.

Figure 4 is a vertical sectional view at right angles to Figure 3, as indicated by line 4—4 of Figure 1.

Figure 5 is a perspective view of the gauge which is used in initially setting the device.

The form of construction selected for illustration may be considered as the preferred construction and while it will be hereinafter rather specifically described, it is to be understood at the outset that within the scope of the invention as claimed, numerous modifications may be made.

The numeral 1 designates a base plate which is adapted to be secured by bolts or the like 2, to a work bench or other appropriate support 3. This plate 1 is provided with an annular upstanding flange 4 whose inner side is screw-threaded for engagement with corresponding threads on another annular flange 5 which projects downwardly from a horizontal, preferably circular table 6, said table having a central opening 7. The edge of the table is provided with an appropriate scale 8 cooperable with a pointer 9 which, by means of a slot 10 and screws 11, is adjustable circumferentially of the flange 4, for a purpose to appear. It will be seen that rotation of the table 6 will

cause the coating screw threads of the flanges 4 and 5, to either effect raising or lowering of said table, and if desired a set screw or the like 12 may be employed to hold said table in adjusted position.

The central portion of the base plate 1 is formed on its upper side with a convex boss 13 and is provided at its lower side with a similar boss 14, an opening 15 being formed through said bosses and the center of the plate. A metal block 16 is provided with a concave lower surface 17 which rests upon the convex boss 13, the upper side of said block being formed with a transverse channel 18 for a purpose to appear. Threaded into or otherwise rigidly secured to the block 16, is a downwardly projecting tubular shank 19, and a hand wheel 20 or some other appropriate form of nut is threaded on the lower end of this shank to engage the convex boss 14. When this hand wheel or the like is loosened, the shank 19 and block 16 may be moved into different angular relations with the table 6, and tightening of said hand wheel or the like will lock the block in the position to which it has been adjusted. The upper end of this block supports a pair of laterally spaced rests 21 upon which the bolt-engaging portions 22 of a bearing cap 23 are intended to rest. A bar 24 is adapted to lie within the bearing cap and its ends are engageable with a pair of loops 25 whose lower ends are appropriately connected with a cross arm 26, the latter being pivoted centrally between its ends at 27 to another shank 28 which passes slidably through the tubular shank 19, a hand wheel or other form of nut 29 being threaded upon the lower end of said shank 28 to contact with the lower end of the shank 19 for the purpose of downwardly pulling the cross arm 26, loops or yokes 25 and bar 24, to tightly hold the bearing 23 upon the rests 21. An appropriate spring 30 may be associated with the shank 28 to raise the latter as the wheel 29 is loosened, permitting the bearing holding means to be readily released.

A file 31 is provided for filing the portions 22 of the bearing cap, said file being provided with guide blocks 32 which are rigid therewith, and are adapted to slide freely upon the surface of the table 6. Preferably, the blocks 32 are formed with slots 33 through which the file 31 passes and in which said file is tightly clamped by thumb screws or the like 34. The lower walls of the slots

33, against which the file is held by the screws or the like 34, are of course uniform distances from the flat lower ends 35 of the blocks 32, so that the lower side of the file 31 will at all times be absolutely parallel with the surface of the table 6.

In setting the device for use, the bearing cap 23 is placed upon the rest 21, the bar 24 is engaged with the cap, the yokes 25 are swung over the ends of said bar 24, and the wheel or the like 29 is tightened to thus securely hold the cap with respect to the block 16. The wheel 20 is now loosened unless this has been previously done, and the work gauge 36 is placed over the bearing cap, said gauge comprising a flat top plate 37 and depending legs 38. The table 6 is at this time lowered so that the legs do not touch it, and the plate 37 rests flatly upon the portions 22 of the bearing 23. The table 6 is now adjusted upwardly and if it is seen that all of the legs 38 will not touch the table top the block 16 and associated parts are angularly adjusted to the necessary extent to cause intimate contact of all of said legs with the table top, while the plate 37 is tightly contacting with the portion 22 of the bearing cap. When this relation of parts is attained, the wheel or the like 20 is tightened. This having been done, the pointer 9 is adjusted to the zero point on the scale 8, which scale is preferably graduated in thousandths of an inch. By now downwardly adjusting the table 6 to any distance necessary, using the scale 8 to determine the extent of this adjustment the device is in readiness for locking with the set screw or the like 12, whereupon the filing operation may be started. By now operating the file 31 with the blocks 32 attached, until the lower end 35 of said blocks come into contact with the table 6, the desired amount of material will be removed from the bearing cap and it is assured that the new surface imparted to the cap, is in a plane absolutely parallel with the plane previously occupied by the old surface, thereby insuring that the bearing cap shall accurately fit the coating part of the bearing when it is reapplied to the shaft.

The invention is rather simple and inexpensive, easily operated and produces exceptionally accurate work. On account of these advantages, the details herein disclosed are preferably followed. However, within the scope of the invention as claimed, modifications may be made as above stated.

I claim:

1. A work clamping and filing device comprising a base, a table having a vertical opening therethrough and mounted above the base for vertical adjustment with respect thereto, a work holding means beneath the table at its opening, means to permit angular adjustment of the work-

holding means relative to the table, and file holding means to slide on the table.

2. A structure as specified in claim 1; together with work clamping means extending downwardly through the work supporting means and movable therewith in its adjustment.

3. A work clamping and filing device comprising a table, means for holding the work to be filed in fixed relation with said table, a file for engagement with the work, file-holding means upon the table, and means for effecting relative angular adjustment of the table with respect to the work-holding means.

4. A work clamping and filing device comprising a table, means for holding the work to be filed in fixed relation with said table, a file for engagement with the work, file holding means on the table, means for effecting relative adjustment of the table and the work holding means to vary the distance between the latter and the file, and means for effecting relative angular adjustment of said table and said work holding means.

5. A work holding and filing device comprising a base, a table above said base and formed with a vertical opening, connecting means between the base and table permitting vertical adjustment of the latter toward and from the former, work supporting and clamping means having a portion passing through said opening in the table, means between the base and the last named means to adjust the work angularly relative to the table, a file for engagement with the work, and guides for said file rigid with respect thereto and adapted to move freely over the table.

6. A work-holding and filing device comprising a support having a convex boss at its upper side and another convex boss at its lower side, said base being formed with an opening passing through said bosses, a table above the base having an opening above the upper boss, connecting means between the table and base for effecting adjustment of the former toward and from the latter, work-supporting means resting on and adjustable over the surface of said upper boss, said work-holding means having a shank passing through said opening of said base and being provided with a work-engaging portion rising through the opening of said table, and a clamping nut threaded on the lower end of said shank and engaging said lower convex boss; together with means on the table for guiding the file used for filing the work.

7. A structure as specified in claim 6; said shank being tubular, work-engaging means for holding the work upon the work-supporting means, said work-engaging means having a shank passing through said tubular shank, and a clamping nut threaded

on the lower end of said second named shank for binding engagement with the lower end of the tubular shank.

8. A structure as specified in claim 6; 5 said shank being tubular, a bar to lie upon the work, a second shank within said tubular shank provided with yokes fitting over the ends of said bar, and a clamping nut threaded on the lower end of said second 10 shank to bind against the lower end of the tubular shank.

9. A work-holding and filing device comprising a base having a convex boss at its upper side, another convex boss at its lower 15 side and an opening through said bosses, a table above the base having an opening over said bosses, connecting means between the table and base permitting vertical adjustment of the former with respect to the latter, work-supporting means including a block having a concave lower side resting on the upper convex boss, said block being formed in its upper side with a channel and being provided with a downwardly projecting 20 tubular shank which passes through the opening of the base, a clamping nut threaded on the lower end of said shank to bind against the lower convex boss, a bar to engage the work, a second shank within said 25 tubular shank provided with yokes to engage the ends of said bar, the upper end of said second shank and the lower end of said yokes being disposed in said channel, and a clamping nut threaded on the lower end 30 of the second shank to bind against the lower end of the tubular shank.

10. A work-holding and filing device com-

prising a base plate provided with work holding means at its center and having an upstanding annular flange, a table above 40 said base plate provided with a depending annular flange having threaded engagement with said upstanding flange, whereby vertical adjustment of the table may be effected with respect to the work supporting means, 45 a file for engagement with the work, and guiding means rigid with said file and adapted for free movement over said table.

11. A work clamping and filing device comprising a circular base having a screw 50 threaded portion, a circular table having a central vertical opening and a screw threaded portion to engage the threaded portion on the base for vertical adjustment of the table toward and from the base, scale graduations around the edge of the table, an adjustably mounted pointer on the base to contact with the scale graduation, an angularly adjustable work holding means at the opening in this table, and file holding means on 55 the table.

12. A work clamping and filing device comprising a base having a vertical opening, a table vertically adjustable on the base and having a vertical opening above 65 that in the base, an angularly adjustable work holding means in said openings to hold the work above the table in a fixed position with respect thereto, said work holding means being operable from beneath the 70 base, and file holding means on the table.

In testimony whereof I have hereunto affixed my signature.

ALBERT C. ASPER.
